Primary Examiner — Catherine R Oliver-Garcia*(74) Attorney, Agent, or Firm* — Hamilton IP Law, PC; Jay R. Hamilton; Charles A Damschen(57) **CLAIM**

The ornamental design for a decoy, as shown and described.

DESCRIPTION

FIG. 1 is a top perspective view of a decoy showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view.

The broken lines depict environmental structure and are for illustrative purposes only and form no part of the claimed design.

1 Claim, 7 Drawing Sheets(56)
